Primary Examiner — Deanna L Pratt(74) *Attorney, Agent, or Firm* — Dinsmore & Shohl LLP(57) **CLAIM**

The ornamental design for a chair, as shown and described.

DESCRIPTION

FIG. 1 is a perspective view of a chair in accordance with the present invention;

FIG. 2 is a front view of the chair of FIG. 1;

FIG. 3 is a rear view of the chair of FIGS. 1-2;

FIG. 4 is a side view of the chair of FIGS. 1-3, the opposite side being a mirror image thereof;

FIG. 5 is a top view of the chair of FIGS. 1-4; and,

FIG. 6 is a bottom view of the chair of FIGS. 1-5.

The broken lines shown in the Figures are for environmental purposes only and form no part of the claimed design.

1 Claim, 6 Drawing Sheets(56)
